BLOWER TYPE OF MATTRESS RENOVATING MACHINE

Ernst Jacob Antoni, Phoenix, Ariz.

Application July 13, 1943, Serial No. 494,571

2 Claims. (Cl. 19—90)

This invention pertains to renovators of the type adapted to process fibrous filling materials such as cotton mattress filling and the like, and has for its objects:

First, to provide a machine wherein the fibers of the substance processed are torn apart and fluffed.

A second object is to provide a machine for the processes above stated, with a minimum of working parts, constructed in a manner so as to be strong and substantial and not likely to break or get out of adjustment.

A third object is to provide a machine in which the flow of material can be regulated so that balling up or cording of material will not take place.

Other objects will appear hereinafter.

I attain the foregoing objects by means of the mechanism and construction illustrated in the accompanying drawings in which,

Figure 1 is an isometric view of the machine with the top removed and a portion of the interior mechanism sectioned off to show the inner working parts;

Figure 2 is an isometric view of the feed end of the machine with the case top removed to show the interior;

Figure 3 is an elevation of the delivery or left hand end of the machine with the case sectioned off to show the interior;

Figure 4 is a midsectional view taken longitudinally through the machine;

Figure 5 is a righthand end view of the machine with the case portion sectioned off to show the interior;

Figure 6 is an isometric view of the main rotor;

Figure 7 is a similar view of the retard;

Figure 8 is a similar view of the outer blower rotor showing a portion of the annular guides;

Figure 9 is a similar view of the outer rotor; and

Figure 10 the bottom half of the screen separator.

Similar numerals refer to similar parts in all views.

Heretofore machines have been made for fluffing, carding and otherwise processing fibrous substances used for filling mattresses and the like, however, these machines tend to tear and cut the fibers and are not adequately provided with mechanism for removing dirt from the fibers as they are in fluffed or expanded condition. The device hereinafter described receives the material to be treated at one end and immediately cards it between the vertical faces of a thresher disk and a stationary retard. The material is then forced by fan blades over a thresher cylinder where it is subject to further fluffing and threshing, and at the same time is blown outwardly against a fine screen such as will pass

dirt particles and broken fibers, and the like, but not the usable fibers. The fiber being thus treated expands as an annular sheet or cylinder around the thresher cylinder and within a 5 cylindrical passageway until it reaches the discharge end by the diagonal position of threshing teeth on the rotor. At the outer end of the fine screen the material is forced into a conical screened area enclosed by a coarse screen, from whence it is drawn out and forced into the discharge pipe by a blower.

Outside of the cylindrical fine screen a second dust removing blower, formed as a squirrel cage, rotates so as to draw an even draft throughout the entire periphery of the fine screen. Dust and broken fibers forced through this screen are collected within the outer case and then further collected and drawn into a hopper from which they are discharged by another centrifugal fan.

Referring to the specific construction, 2 indicates a box case which encloses the working parts. Operating on a longitudinal shaft 3, within this case is the main cylindrical thresher rotor 4 which consists of two end disks 5 and 6 connected by four rails 7, which carry threshing teeth 8 arranged in rows diagonally aligned relative to the axis of the rotor. Between these rails are slats forming fan blades 10. Adjacent to disk 10 is a fluffing or thresher disk 12 which carries a large number of teeth extending directly outward from its outer face. On the rim of this wheel are a number of diagonally positioned fan blades 14, provided with teeth on their outer edges, and having their outer corners 11 beveled off so as to permit free passage of material over their outer edges. These may be termed feed blades. Positioned adjacent to disk 12 is a stationary disk 20 attached to the near edge of the box case. This is termed a retard, and has teeth extending outwardly from its inner face in juxtaposition to the teeth on disk 12. A feed hole 13 is cut in this disk through which the material to be processed is fed.

Surrounding the main thresher rotor just described is a fine screen (Fig. 10) 22. This is braced by suitable means and on its inside provided with annular baffles or ruffles 23, to slow up the progress of material throughout its length. 50 In addition to these there are rows of teeth 24, arranged in axial longitudinal alignment between these baffles. This screen is made in halves, the upper half being attached to an upper removable portion of the case, and the lower half fixed 55 within the case as shown particularly in Figures 1 and 2. On shaft 3 and beyond the main rotor is a blower fan 25 which draws a suction longitudinally from the end of the rotor and discharges through a tangential pipe 26. Between 60 the discharge or far end of screen 22 and this

fan housing is a coarse screen 27 which has a somewhat conical outer shape. The object of the screening here is to permit fresh air to be drawn through the material itself after it leaves the annular area between the main rotor and the fine screen, and draw it into the discharge fan 25 without creating a suction on the material while within said annular area, and without drawing dust from it.

Annular races 30 surround the ends of screen 22 to accommodate rollers 32 at either end of the squirrel cage rotor, 33. At each end of this rotor there are large gear wheels 34 which are driven by spur gears 35 on shaft 36, and this in turn is driven by pulley 37 connected by belt 38 to a driving pulley 15 on shaft 3. The squirrel cage rotor rotates around screen 22 in such a way as to create an even outward draft to collect dirt and undesirable substances blown through screen 22 by the blades 10 on the main rotor 4. This material is drawn into the interior of case 2 and collects in pan 40, from which it is drawn by the blower 41 and discharged through pipe 42. Blower 40 is driven by a shaft 43 through gearing 44. Shaft 43 is driven by a pulley 45 and belt 38. Shaft 3 is driven in any conventional manner from a convenient power source at about 1200 revolutions per minute.

Operation

The machine is set up with power source driving shaft 3. When shaft 3 rotates the other shafts 36 and 43 are driven by belt 38. The main thresher rotor 4 rotates in a clockwise direction, as viewed in Figures 1, 2, and 6. Squirrel cage blower operates in a direction to create an outward draft, as above explained. Material discharge blower 25 operates on shaft 3, and dust removing blower 41, on the shaft and gearing above described.

Material is fed through hole 13. Upon coming in contact with disk 12 it is threshed between the rotating teeth on this disk and the stationary teeth on the retard 20 and at the same time given a centrifugal action. As it nears the rims of these parts, it is caught by the diagonally positioned fan blades 14 and forced into the cylindrical area enclosed by screen 22. It proceeds along this annular working area due to the action of the rows of thresher teeth 8 diagonally arranged, as shown. These teeth are provided with right angular bends, at their ends, forming hooks 47 pointing in the direction of rotation. This prevents rolling or cording of the material being processed. The material is subjected to a threshing action between teeth 8 on the rotor and teeth 24 on screen 22, and at the same time a beating and blowing action by the rotor blades 10. The baffles 23 hold the material back so that it does not work thru the machine too fast. Thus the material is threshed and the dust and dirt blown out as it is forced along the length of screen 22.

After the material has reached the far or discharge end of the annular space between rotor 4 and screen 22, it is lodged in the conical catch chamber formed by coarse screen 27. From this space it is drawn out by fan 25, together with a quantity of clean air drawn through this coarse screen and discharged through pipe 26.

Since screen 27 has a large mesh suction thru it has less resistance than thru screen 22. There-

fore, the material discharge blower does not draw a draft thru this screen such as would be likely to pick up dust from the material being threshed. It is to be noted that there is a partition 28 at the discharge end of screen 22 which supports that end of the screen and separates the dust receiving compartment 29 of the case from the area surrounding screen 27. This partition is cut horizontally so as to be part of the upper and lower halves of the outer case. A partition 31 in the lower half of the case, acts as a support for the outer end of screen 27. The space between the retard 20 and rotor disk 12 may be termed a receiving chamber. The space surrounding screen 27 may be left open since air is drawn inwardly thru this case. Any suitable hopper or feed mechanism may be attached to feed hole 13.

Whereas I have described one example of my invention, I realize it is subject to many modifications and substitutions, therefore I wish to be limited only by the following claims.

I claim:

1. A renovating machine comprising in combination, an outer case, a partition dividing said case longitudinally to form a dust collecting compartment, and a discharge compartment; a thresher rotor operative in said dust receiving compartment; a cylindrical fine screen surrounding said thresher rotor, said rotor having a plurality of longitudinally extending bars, and beating blades alternately positioned around its periphery, said bars carrying diagonally extending rows of teeth having hooks extending in the direction of rotation, said screen being provided with annular ruffles, and longitudinally extending rows of thresher teeth; diagonally positioned feed blades positioned around the feed end of said rotor; a feed thresher disk having axially extending teeth on its outer face attached to the feed end of said rotor, a retard plate having teeth facing said feed rotor, and attached to the inner face of the feed end of said case, and having a feed hole formed in and extending through it and the adjacent case end; a conical coarse catch screen attached to the discharge end of said fine screen, a material receiving blower drawing thru this screen, and adapted to discharge thru a material discharge pipe; a dust collecting rotor operative around said fine screen; and a dust receiving and discharge blower operative in the bottom of said dust compartment.

2. In a material renovating machine threshing and cleaning mechanism including, in combination a thresher rotor operative within a cylindrical screen, feed mechanism operative at one end of the annular space between said screen and said rotor periphery, and a discharge chamber arranged at the opposite end; said rotor being operative on a shaft, and composed of end disks attached to axially extending bars annularly arranged, and having diagonal rows of outwardly extending teeth, hooked at their outer ends in the direction of rotation, thruout their length, and flat beater fan blades, interspersed between said bars, said screen having a plurality of spaced annularly extending ruffles on its inner surface, and longitudinally extending rows of inwardly extending teeth positioned around its inner face between said ruffles.

ERNST JACOB ANTONI.
